United States Patent Office

Des. 184,315

Patented Jan. 27, 1959

184,315

HANDLE FOR BOTTLE TYPE CONTAINERS

Webb C. Jennings, Rocky River, Ira T. Swartwood, Lakewood, and Rudolph A. Sampson, Cleveland, Ohio

Application October 11, 1957, Serial No. 48,072

Term of patent 14 years

(Cl. D58—26)

Fig. 1 is a top plan view of a handle for bottle type containers embodying our new design;

Fig. 2 is a side elevation of the handle;

Fig. 3 is an end view of the handle as viewed from one side; and

Fig. 4 is an end view of the handle as viewed from the opposite side.

The portions shown in broken lines are for purpose of illustration only.

We claim:

The ornamental design for a handle for bottle type containers, substantially as shown and described.
